AUTOMATIC CLOSET LIGHT FIXTURE

Martin B. Beline, Chevy Chase, Md., assignor to
 Slater Appliances, Inc., Woodside, N. Y., a corporation of New York

Application January 6, 1950; Serial No. 137,189

2 Claims. (Cl. 240--2)

1
 This invention relates to a lighting fixture for closets which is automatically operable by the opening and closing of the closet door.

It is the object of the present invention to provide a compact and simple electric light fixture for mounting in the corner of the frame of a closet door so that the same may illuminate the closet upon the opening of the door and will be automatically extinguished upon the closing of the door.

It is another object of the present invention to provide a rugged and economical lighting fixture which is self-contained by the provision of a light socket, switch and extension cord with attachment plug as part thereof, and which may be universally mounted in all types of closets in order to conveniently provide for the illumination of a closet in response to the opening of the closet door. The unit is capable of rapid installation by virtue of its self-positioning characteristics, and requires no tools or wiring connections, so that anyone may install the same without special skill or training.

It is a further object of the invention to provide an automatically operating closet fixture of low cost which is noiseless in operation and which requires no critical maintenance or servicing.

It is a further object of the invention to provide a compact lighting fixture for illuminating the interior of a closet which may be easily attached to and removed from the closet door frame and which may be connected to the most accessible power outlet receptacle to provide illumination for a closet where such was lacking heretofore. In such closets where means for illumination has already been provided, the instant invention may be installed to provide an automatic control of the closet illumination by the utilization of the outlet receptacle in the closet with the unit in accordance with the present invention.

It is a further object of the invention to provide an electric fixture for a closet which is compact and neat in appearance, which is substantially inconspicuous and one which affords an efficient illumination of the closet with minimum power consumption. The mounting of the unit adjacent to the hinge side of the door affords substantially no obstacle in the frame opening in the course of handling articles which are placed into and taken from the closet.

The invention proceeds upon the principle of providing a compact housing, preferably stamped from sheet metal, having at least one rectangular

2
 corner formed by two of its lateral walls which renders it accurately positionable within the corner of a closet door frame opening against the horizontal and vertical members of the door stop. Flanges extending transversely to the lateral walls of the housing assure an accurate positioning of the housing within the corner adjacent to the hinge side of the door, and the unit may be easily affixed to the horizontal and vertical members of the door stop by thumb-tacks which extend through openings in the lateral walls and penetrate into the faces of the respective members of the door stop. The housing is provided with a normally closed switch protruding from the front face thereof and an electric lamp socket and extension cord terminating in an attachment plug extending from the rear face thereof. The mounting of the unit in the upper corner of the frame adjacent to the hinge side of the door assures a positive operation of the switch by the opening and closing of the door which is not affected by a warped condition of the door or the frame or by faulty and uncertain closing and opening operations of the door. The electric lamp, which is adapted to be mounted in the socket, because of its location, provides the most efficient illumination of the contents of the closet. The power supply conductors extending from the housing and terminating in any suitable attachment plug may be led to the exterior of the closet to the most accessible outlet receptacle or else to the electric outlet which may have been provided already in the closet.

Other objects and purposes will appear from the detailed description of the invention following hereinafter, taken in conjunction with the accompanying drawings, wherein

Fig. 1 is a perspective view of the lighting fixture mounted in the corner of a closet door frame opening for operation;

Fig. 2 is a perspective view of a room having the closet provided with the lighting fixture in accordance with the invention and showing the connection thereof to a power outlet receptacle in proximity to the closet;

Fig. 3 is a front elevation of the lighting fixture as viewed from the outside of the closet;

Fig. 4 is a rear view of Fig. 3;

Fig. 5 is a vertical sectional view along line 5-5 of Fig. 3;

Fig. 6 is a vertical sectional view along line 6-6 of Fig. 3; and

Fig. 7 is a vertical sectional view along line 7-7 of Fig. 3.

In Figs. 1 and 2 is shown a conventional closet door frame F having the closet door D hinged along the right side thereof by means of hinges H and provided with a door stop S running along the lateral and top sides of the closet. The door stop S comprises the horizontal member having the face 1 and edge 3 and the vertical member having the face 2 and edge 4. The lighting fixture in accordance with the present invention is mounted preferably in the corner of the horizontal and vertical members of the door stop adjacent to the hinged side of the door D. This fixture consists essentially of a housing 5 which is formed of sheet metal of such thickness that the interposition of the flanges 15 and 16 of the housing unit between the door stop and the door in nowise affects the closing of the door adjacent to the door stop S.

The housing may be formed of rectangular outline from a central portion 9 (Fig. 4), provided with two apertures therein for purposes explained hereinafter, from which is bent lateral walls 10 and 11 at right angles to each other, as well as lateral walls 12 and 13 opposite walls 10 and 11, respectively. The walls 10 and 11 in addition to forming the walls of the housing are extended further to form fastening portions 10' and 11', respectively, which are adapted to fit closely against the faces 2 and 1 of the door stop S. A small opening 18 is provided in extension 10' and another opening 17 is provided in extension 11' into which are adapted to be inserted thumb tacks 7 which penetrate into the horizontal and vertical members to constitute the sole fastening means of the housing unit in place. A transverse flange 15 extends transversely from the lateral wall 11-11' and another flange 16 extends transversely from the lateral wall 10-10', these flanges being adapted to abut closely against edges 3 and 4 of the door stop to provide for the accurate placement of the housing within the corner of the door frame.

A detachable cover 19 of sheet metal is provided for the front face of the housing which is adapted to be resiliently sprung onto the housing by the provision of punched projections 19a (Fig. 7), which are adapted to be received between tongues pressed inwardly from the lateral walls of the housing near the free edges thereof remote from wall 9, and the housing walls. As shown in detail in Fig. 7, tongue 13a is punched inwardly from the wall 13 leaving the opening 13b in the plane of the wall into which opening is adapted to spring the tongue 19a of the lateral flange of the cover 19. Similar tongues and openings are provided in each of the other lateral walls 10, 11 and 12 which cooperate with the spring tongues 19a, as shown in Fig. 3, to maintain the cover 19 securely in place.

The cover 19 serves to mount the socket 20 and the switch 30 within the housing. A screw or rivet 27 having its head countersunk in the outer face of cover 19 serves to fasten the socket 20 within the housing, which socket protrudes slightly from the rear face of the housing through the larger one of the openings provided in wall 9. The second opening in wall 9 is lined with a grommet 25 of rubber or the like, through which extends the wires 23 and 24 into the housing from a cord which terminates in an attachment plug which is adapted to be connected to an outlet receptacle.

The switch housing 30 within the housing 5 is also held by the cover 19. An insulating button 31 forming part of the switch 30, extends

through the cover 19 and is adapted to be moved inwardly upon the closing of the door against the force of the spiral spring 35 within the cylindrical casing 30. In the illustrated embodiment of the normally closed switch, the circuit through the switch is completed between the spring arms 34 when the door is opened by the interposition of a conductive segment 33 mounted on the end of an insulating bar 32 when the switch button 31 is in freely protruding position in consequence of the force exerted thereagainst by spring 35. Upon the inner movement of the button 31, the conductive segment 33 passes from between the ends of the spring fingers 34 (Fig. 6) so that the circuit between these fingers is now broken by the insulating bar 32.

Only the button 31 protrudes beyond the plane of the housing and its cover so that faulty operation of the switch or marring of the door is excluded. The thickness of the flanges 15 and 16 is so slight that the interposition of them between the door-stop and the door is well within the permissible tolerances allowed carpenters in the fitting of doors within door frames.

The socket 20 is a conventional one embodying the central terminal 21 in conjunction with the screw terminal 22 which are connected in circuit with the switch by means of conductors 23 and 24 within the housing. The slight extension of the socket 20 beyond the rear wall of the housing gives rise to a unit having a small moment of inertia so that even with the lamp L disposed in the socket, no substantial forces arise which tend to dislodge the housing from the corner of the frame. The closing of the door against flanges 15 and 16 serves to maintain the unit securely within the corner and in view of the disposition of the switch button 31 along the inner part of the unit, the moments which may be actually transmitted thereby to the housing are of small degree, and these are effectively counterbalanced by the spring 35 within the switch housing 30.

The housing in accordance with the present invention is capable of universal application to closet doors of all types. In those cases where the door is hinged on the left side rather than on the right side, the housing unit is turned 90° in order to bring the flange 16 in horizontal position and the flange 15 in vertical position. Of course, the device is operable on either alternating or direct current.

The length of the electric cord 23 and 24, for example, fifteen feet, is adequate to be led along the side of the closet to the exterior thereof along the baseboard for connection to the nearest outlet receptacle R (Fig. 2). In those cases where an electric outlet is already provided in the closet, a shorter length of wire may be used for connection to the outlet.

The provision of the lamp at the top of the door frame provides a more efficient illumination than an electric lamp mounted in the top of the closet where much of the light is cut off by one or more shelves provided in the closet.

The housing described above lends itself to attachment and connection by means of thumb tacks in thirty seconds. In those cases where the closet framework is formed of metal, metallic fasteners may be used in lieu of thumb-tacks without sacrificing the many advantages of the invention.

The unit is easily detachable from the closet door frame in order to enable a party who has installed the same but temporarily to remove it

for installation in another closet, thus giving rise to an installation which is much more economical than one entailing complex wiring of the closet for illumination.

While I have described my invention as embodied in specific form and as operating in a specific manner for purpose of illustration, it should be understood that I do not limit my invention thereto, since various modifications will suggest themselves to those skilled in the art without departing from the spirit of my invention, the scope of which is set forth in the annexed claims.

I claim:

1. In a device of the class described, a closet-light fixture for mounting on the door-stop in the upper corner of a closet door frame opening adjacent to the hinge side of the door, said fixture comprising a housing and mounting flanges attached thereto consisting of two sheet-metal lateral walls perpendicular to each other adapted to fit within the corner of a door stop and terminating in fastening portions beyond the boundaries of said housing for affixing the ends of said walls to the corresponding faces of said door-stop, each of said fastening portions having a small opening therein for the reception of a pointed fastener for penetration into the respective faces of the door-stop, positioning flanges extending perpendicularly to said lateral walls and adapted to be disposed closely adjacent to the horizontal and vertical edges of the door-stop and between said edges and the door in its closed position, a reciprocating switch within said housing protruding from the front thereof and controllable by the opening of the door to

complete a circuit therethrough, a lamp socket in said housing facing the rear thereof for receiving an electric lamp therein, and electric conductors terminating in an attachment plug connected to said switch and socket and extending from said housing for connection to a source of power supply for the automatic energization of the electric lamp in response to the opening of the closet door.

- 10 2. A closet-light fixture comprising a switch housing, mounting flanges attached thereto consisting of two sheet-metal lateral walls perpendicular to each other adapted to fit within the corner of a door stop and terminating in fastening portions beyond the boundaries of said housing, positioning flanges extending transversely to said walls at right angles to each other in a common plane, and a normally closed electric switch mounted in said housing and provided with an actuating member protruding from one side of said housing beyond said common plane.
